METHOD AND MEANS FOR HEAT EXCHANGER CONTROL

Chester D. Hall, Millard L. Brown, Garrett T. Thurman, and Richard A. Kinz, El Paso, Tex., assignors to Chevron Research Company, a corporation of Delaware

Filed Mar. 17, 1965, Ser. No. 440,481

4 Claims. (Cl. 165—1)

This invention relates to shell-and-tube heat exchangers, and more particularly to shell-and-tube heat exchangers arranged to reduce thermal stress within their shell sections. Still more particularly, it relates to internal bypass valving systems to control the quantity of tube-side fluid passing through such exchangers.

In this application, the term "shell-and-tube heat exchanger" refers to an exchanger having, among other things, (1) a tube bundle for conveying a tube-side fluid in at least two passes through the exchanger; (2) a shell section for supporting the tube bundle and conveying shell-side fluid in at least a single pass through the exchanger in heat transfer contact with the tube-side fluid; (3) a channel section attached at one end of the shell section to provide separate inlet and outlet chambers for the tube-side fluid—these chambers preferably being provided by means of a baffle longitudinally disposed within the section; and (4) an arrangement for reducing the thermal stresses between the tube bundle and the shell during operation of the exchanger. The last-mentioned arrangement typically includes a floating header section attached to the shell at an end opposite the channel section to allow differential expansion of the tube bundle relative to the shell and also to provide for reversal of the tube-side fluid. However, it is intended that other stress-relieving arrangements may be used in conjunction with this invention; for example, by disposing a U-tube bundle within the shell.

It is a particular object of this invention to provide a rugged and inexpensive bypass system for a shell-and-tube heat exchanger that will permit internal control of tube-side fluid passing through the exchanger, but such control to occur without a corresponding increase in tube-side system pressure. In carrying out this object, the exchanger in accordance with the invention is constructed with an internal valve system for connecting tube-side fluid directly across the channel baffle of the exchanger. By such an arrangement, the tube-side fluid passes directly from the inlet to the outlet chamber of the exchanger without first passing through the shell section. In a preferred form of the apparatus, this valve system includes a valve stem entering the channel section through one of the channel nozzles, one end of stem preferably connecting to a valve plug in contact with a valve seat or sleeve welded to the channel baffle. The sleeve extends through an aperture in the channel baffle and includes vertical slots extending parallel to the axis of the stem; the slots increase in height as the plug and stem undergo vertical movement to adjust the fluid contact between the inlet and outlet chambers. The capacity of the valve system may be varied, for example, as a function of the exhaust temperature of the shell-side fluid to reduce the heat transfer efficiency of the exchanger and provide a desired temperature level within the exchanger without increasing the system pressure or adding expensive piping and valves to the exchanger. Furthermore, the system may be incorporated within existing exchangers with minimum expenditures of time and material. Additionally, the variation in capacity provided by the valve may be co-ordinated with the amount of fluid externally bypassed around the exchanger to increase the control range of the external system.

2

Other objects and advantages of the invention will become more apparent from the following detailed description, in which:

FIGURE 1 is a schematic diagram of a shell-and-tube heat exchanger incorporating the invention;

FIGURE 2 is a sectional view taken across line 2—2 of FIGURE 1 illustrating an internal bypass valving system;

FIGURE 3 is an elevational view taken along line 3—3 of FIGURE 2;

FIGURE 4 is a side view taken along line 4—4 of FIGURE 2;

FIGURE 5 is an enlarged detail of the internal bypass system of FIGURE 2; and

FIGURE 6 is a sectional view taken along line 6—6 of FIGURE 5.

Referring now to the drawings, particularly FIGURE 1, shell-and-tube heat exchanger 10, constructed in accordance with the invention, transfers thermal energy between adjacent fluid circuits within the exchanger; i.e., between shell-side fluid 11 entering the exchanger at inlet shell nozzle 12 and tube-side fluid 13 entering the outlet exchanger nozzle at inlet channel nozzle 14. In conventional manner, the shell-side fluid may be baffled to undergo a sinuous path through the shell section 15 and exits, after a single pass through the shell, at outlet shell nozzle 16. The tube-side fluid is conveyed through shell-side section in at least two passes by a multiplicity of tubes 17 known as a bundle (see FIGURE 2). In more detail, the tube-side fluid:

Enters the exchanger at channel section 18,
Passes through the tube bundle 17 to header section 19,
Returns through the tube bundle to channel section 15,
and

35 Thereafter passes from the exchanger via outlet channel nozzle 20.

Pressure is applied to both fluids by pumping units, not shown.

40 As indicated in FIGURE 1, the exchanger 10 may be used in conjunction with an external bypass piping network 21 connected between the inlet and outlet nozzles of the channel section. The purpose of the network is to carry a portion of tube-side fluid around the shell section to lower the heat transfer efficiency of the exchanger as changes occur in external process conditions. It is, of course, intended that the amount of tube-side fluid passing through the external network be varied, as by valves, to provide desired temperature conditions within the exchanger. However, if a change in operative conditions occurs in the tube-side fluid system, for example, there may be corresponding increases in the efficiency of the heat exchanger that cannot be nullified by the bypass network. As the exchanger overheats, or alternatively 50 undercools depending on the function of the tube-side fluid vis-a-vis the shell-side fluid, the effect may be to render the exiting shell-side fluid in compatible with the process external of the exchanger.

55 Since a change in operating condition usually occurs after the heat exchanger is designed and functioning within a given process, it is important that the modification to the exchanger to increase bypass capacity be accomplished in minimum time and, furthermore, provide very little change in over-all tube-side system pressure. Additionally, since the external piping network is relatively expensive to modify, it is also important that the modification incorporate minimum additions of piping and/or valves.

60 In carrying out these objects, the exchanger 10, in accordance with the invention, is provided with an internal bypass system 30 (FIGURE 2) located in the interior of channel section 18. In more detail, the sys-

tem 30 includes a valve seat or sleeve 31 open at its ends to connect inlet chamber 32 of the channel section with outlet chamber 33 to increase the quantity of tube-side fluid bypassing the shell section 15. As indicated, sleeve 31 is anchored at its upper end to chamber baffle 34 and extends downward, as viewed, through aperture 35 in the baffle into the lower chamber 33.

Contact between the sleeve and channel baffle occurs only at the upper end of the sleeve. In operation of the exchanger, the sleeve is therefore free to expand relative to the baffle to reduce the occurrence of stress concentration along its length. Inasmuch as the sleeve is closed at its lower end, slots 36 are provided in the side wall to permit fluid communication of the chambers. These slots are circumferentially separated by ribs 37 for sufficient width to withstand system pressure as the tube-side fluid is bypassed through the sleeve.

The diameter of the sleeve and the width and height of the slots should be large enough to reduce the capacity of the tube-side fluid passing through the exchanger to an effective level. That is, the amount of tube-side fluid passing through the valve system 30 must be to a sufficient level to reduce the heat transfer efficiency of the exchanger whereby to provide the shell-side fluid with a desired exhaust temperature.

Flexibility in controlling the flow rate of the tube-side fluid through the sleeve 31 is provided by plug 38. In this embodiment, the plug is preferably frustoconically shaped to facilitate its movement through the sleeve and includes a lower edge 40 (FIGURE 5) in contact with the side wall of the sleeve. An arcuate central surface 41 extends upward and away from the edge; its purpose is to deflect the tube-side fluid through the slots with minimum turbulence. Contact between the plug and sleeve occurs only in one plane—in the intersection of edge 40 with the ribs 37. Movement of the plug relative to the sleeve to provide a corresponding change in slot height 39 is therefore relatively easy to achieve.

In this embodiment, control of plug 38 is provided by the vertical movement of stem 42, to which the plug is attached; but other valve and control arrangements can be used if desired. A requirement in such systems, however, is that the stem 42 or other control means for the valve pass into the exchanger through the channel nozzles to minimize stress concentrations within the shell. The lower end of the stem 42 is secured to the plug by a reducer 44 attached to the stem by welding. The reducer also includes threads at its lower exterior for attachment to the plug. The plug is keyed to the reducer by safety wire 45. When repairs are necessary, this arrangement makes for easy replacement of damaged parts.

The upper end of the stem is attached to chain wheel 50 at the exterior of the exchanger by which an operator can adjust the slot height of the sleeve. In this arrangement, pressure integrity is maintained by passing the stem from the exchanger through a pressure-tight bonnet 51 attached to a flanged support 52 above the channel nozzle 14. Flanged inlet piping 53 is attached to the channel nozzle below support 52 but is preferably arranged to form a Y-junction with the support to allow the alignment of the stem 42 within both the bonnet 51 and the sleeve 31. Although the axes of the support 52, channel nozzle 14, and the sleeve 31 are illustrated as collinear for this purpose, the stem could be constructed with flexible joints along its length to compensate for deviations in alignment.

Pressure-seal bonnet 51 includes a flanged base 55 attached to support 52. Above the base is attached a yoke 56 (see FIGURE 4) terminating in threaded hub 57 through which the stem 42 threadably engages. Bolts 58 attach to bonnet 59 and apply pressure of stuffing box 60 to prevent flow of fluid from the interior of the exchanger.

Rotation of the stem from a level below chain wheel 50 is provided by endless chain 61 riding over rollers 62,

through guides 63, and thence around the chain wheel 50 (see FIGURE 3). Guides 63 are stationarily fixed in space by means of yoke 64 rotatably attached to the stem. As indicated in FIGURE 4, rollers 62 are attached to a central shaft 65 journaled at its ends to frame 68. The lower part of the frame 68, in turn, is attached to the flange of pipe 53 and to the base 55 of bonnet 51 as indicated.

The relative height of the plug above the end wall of the sleeve will vary depending upon the operating conditions of the exchanger. In general, it will be in the order of 1 to 5 inches long to provide flexibility in adjusting varying exchanger operating conditions.

Correct spacing of the plug relative to the end wall of the sleeve may be preferably determined under process operating conditions. Initially the plug is preferably positioned in a plane intersecting the chamber baffle 34; but, after the exchanger has been put on-stream, the stem and plug undergo downward movement, as viewed, to increase flow of the tube-side fluid through the internal valving system. As viewed in the figures, as the plug clears the upper end of the slots, tube-side fluid passes downward through the sleeve and then is deflected in radial directions by the arcuate central surface of the plug through the slots 36 into the lower chamber 33 and thence removed from the exchanger by outlet nozzle 20. As the amount of tube-side fluid increases in fixed increments occurring, say every five minutes, the exhaust temperature of the shell-side fluid is monitored. When the desired operating exhaust temperature is achieved, movement of the stem is terminated, positive locking of the stem occurring by virtue of screwable connection between the stem and hub 57 of the bonnet 51 exterior of the exchanger.

Utilization of existing structure of an exchanger to provide bypass control of the tube-side fluid (where modification of an existing exchanger is necessary) is a further advantage of the present invention. For example, aperture 35 may be provided in the baffle 34 without the necessity of the baffle being removed from the exchanger. Likewise, other parts of the system are similarly attached to the exchanger with minimum expenditure of time and money.

Further flexibility of the exchanger internal bypass system may be achieved by using control features of the external bypass network 21. To provide a maximum control capacity through the external bypass network, the adjustments in the internal valve previously described are preferably undertaken after the capacity of the external bypass system has been reduced as to say one-half capacity. Consequently, after a desired plug-sleeve setting for the internal valve is achieved, the external piping network will provide maximum flexibility in adjusting the rate of flow of tube-side fluid through the exchanger, as changes in operating conditions occur.

In many applications, automatic response of the internal valving system to changes in process conditions may also be desirable. On an automatic system compatible with existing exchangers, a temperature-sensitive transducer may be arranged to be supported in shell exhaust nozzle 16. The transducer has bimetal elements whose movements reflect any changes in temperature of the shell-side fluid. The bimetal elements are designed to close a relay as the temperature increases that in turn trips a motor through a timing circuit. The motor drives the valve controllers, as for example stem 42 in rotation causing vertical movement of the controller relative to the valve seat. The purpose of the timing circuit is to prevent the controller from being overdriven during adjustment of valve aperture. A delay interval of five minutes between relay and motor actuation is sufficient for this purpose. It is to be noted that the system may be further modified to vary the direction of the rotation of the controller, either clockwise or counterclockwise, as a

function of the sign of the transducer signal to add further flexibility to the system.

Various changes in the structure shown and described will occur to those skilled in the art. All such changes are intended to be included within the scope of the intended claims.

We claim:

1. In a heat exchanger control system including a shell- and tube-heat exchanger having a shell section for conveying shell-side fluid through said exchanger, a tube bundle within said shell section for conveying tube-side fluid through said exchanger in heat transfer contact with said shell-side fluid, an inlet-outlet channel section for said tube-side fluid in operative contact with said tube bundle, a channel baffle separating said channel section into an input chamber and an output chamber, each of said chambers in fluid contact with one end of said tube bundle, and an external bypass piping network connected to said exchanger for externally bypassing a portion of said tube-side fluid about said exchanger so as to control the efficiency of heat transfer within a predetermined range within said heat exchanger, the improvement comprising an internal bypass valve system for said tube-side fluid within said channel section adapted to extend the range over which said heat transfer is controlled, 25 said internal bypass valve system including

(a) a sleeve means attached to and extending through said channel baffle, said means having an aperture therein to place said two chambers in fluid communication, and

(b) control means operatively connected to said sleeve means for varying the rate of flow of said tube-side fluid between said chambers and thereby extend predetermined control range of said system.

2. The combination of claim 1 in which said control means includes actuating means adapted to initiate operation of said control means from the exterior of said exchanger.

3. The combination of claim 1 wherein said control means includes a valve plug operatively connected and seated within said sleeve means, a valve stem connected at one end to said valve plug and extending exterior of said exchanger for moving said stem relative to said sleeve; and pressure seal means exterior of said exchanger

10
15

5

operatively connected to said stem and attached to a portion of said exchanger.

4. A method of extending the range of a heat exchanger control system which includes a heat exchanger adapted to pass tube-side fluid from an input-output channel section having a longitudinal channel baffle therein to divide said channel section into first and second chambers, to a multiplicity of tubes within a shell section attached to said channel section so as to place the tube-side fluid in heat transfer contact with a shell-side fluid passing through the shell section exterior of the multiplicity of tubes, and an external bypass piping network connected to said exchanger, comprising the steps of:

- (a) forming an aperture in said channel baffle in said channel section to place said first and second chambers in direct fluid contact;
- (b) arranging a normally closed valve means in operative contact within said aperture;
- (c) flowing the tube-side fluid and shell-side fluid in heat transfer contact through said exchanger;
- (d) simultaneous with step (c) flowing tube-side fluid in the external piping network about said exchanger at full capacity so that a portion of said tube-side fluid bypasses the exchanger to control the efficiency of heat transfer between the fluids within the exchanger within a predetermined range;
- (e) incrementally opening said valve means in said channel section to pass a portion of tube-side fluid through said aperture so as to extend the heat transfer control range of the system, and
- (f) terminating said increase in flow of said tube-side fluid when the efficiency of heat transfer between the fluids in the exchanger reaches a desired level.
